UNITED STATES PATENT OFFICE.

DAVID BOYLE, OF CHICAGO, ILLINOIS.

APPARATUS FOR ATTEMPERATING OR COOLING BEER.

SPECIFICATION forming part of Letters Patent No. 320,618, dated June 23, 1885.

Application filed July 12, 1884. (No model.)

To all whom it may concern:

Be it known that I, DAVID BOYLE, a resident of Chicago, in the county of Cook and State of Illinois, have invented certain new and useful Improvements in Apparatus for Attemperating or Cooling Beer; and I do hereby declare the following to be a full, clear, and exact description of said invention, sufficient to enable others skilled in the art to which it appertains to make and use the same.

The invention relates to that class of devices used to cool liquids and to maintain the same at a low uniform temperature, said devices being more especially applicable to the cooling of beer in the beer-vats of breweries.

In lieu of the ordinary swimmer, which, with its charge of cooling material, floats upon the surface of the beer, it is the object of the invention to employ a solution of brine or the like as the cooling medium, the same being artificially cooled, as well understood, and being forced to circulate in closed pipes through the liquid to be attempered. The closed pipes being submerged in the heated beer of the vats, enables the cold brine in course of circulation to rapidly abstract the heat and to reduce the beer to a low even temperature. When this desired stage is reached, it is plain that the beer can be easily kept at such point by merely regulating the supply of the cooling agent circulating within the pipes.

The facility and readiness with which the desired uniformity of temperature in the beer may be promptly controlled is an especial point of advantage possessed by this type of mechanism over the old style of swimmer, which it is designed to replace.

My invention consists in the combination, with the vat and with the stationary supply and return pipes for the cooling agent, of the vat-pipe swiveled thereto, said vat-pipe being bent in horizontal coil located near the top of the vat, and being provided with suitable mechanism—such as cord and catches—to hold the pipe in either raised or lowered position. By reason of such organization and location of the parts the more highly-heated portions of the beer are constantly subjected to the cooling influence. A local circulation of the beer within the vat is consequently established, the

hotter portions rising to the surface, and upon being attempered by the cooling agent in the vat-pipe falling again to make room for further portions of the hotter liquid. The 55 vat-pipe being conveniently sustained by the vat itself relieves the swivel-joint from the strain and breakage to which it would otherwise be subject, while the cord and catches enable the workman to quickly adjust and hold the vat-pipe in either raised or lowered position.

In the accompanying drawings, forming part of this specification, like letters of reference denote like parts throughout.

Figure 1 is a view in elevation of a beer-vat, broken away at the side to show the position of the cooling appliance constituting my invention. Fig. 2 is a view in plan of the vat with the cooling devices attached thereto. 70 Figs. 3 and 4 are detail views in section of the swivel-joints between the vat-pipe and stationary conduits.

The vats A, mounted on usual staging above the floor of the brewery, are each provided 75 with an inlet-conduit, a, and outlet-conduit a', connecting, respectively, with the supply-pipe 1 and return-pipe 2 of the circulating system. These pipes, as well understood, are in communication with the force-pump, and serve to 80 deliver the cold brine to the individual vat-pipes, and to receive the same again after passing therethrough. Said supply and return pipes may be conveniently arranged beneath the staging, so as to be readily accessible, and at the same time to avoid spoiling the beer in event the joints of the pipes should start and cause leakage of the brine. The conduits a a' rise at the sides of vat A, and have swiveled thereto the vat-pipe b, which, as 90 shown, is bent in simple coil and sustained at b' in bearings on the vat. The swivel or union joint between the vat-pipe b and conduits a a' may be of any convenient and well-known form—such, for example, as that shown in Fig. 95 3, where the cap-piece b² of vat-pipe b' is ground true and snugly seated within the union-piece b³. A nut, b⁴, threaded to the cap and union-pieces, may tightly force these together, or, by slightly loosening said nut with 100 a wrench, allow said cap-piece and its attached vat-pipe to swivel or turn about its seat in

union-piece b^3 . A stem-valve, b^5 , regulates the flow of liquid passing in conduits $a a'$ and the vat-pipe b ; or, again, as shown in Fig. 4, the vat-pipe b and collar b^6 may turn within 5 the stuffing-box formed at end of the union-piece b^1 , as well understood. In this latter form of swivel-joint the regulating-valve, instead of being in the union-piece, as in Fig. 3, may be located at some convenient point on the 10 conduits $a a'$. The vat-pipe b , being swiveled as described, may be lifted at any time entirely free from the vat without risk of leakage or need of shutting off the circulating brine. A pulley, 3, rope 4, and catches 5 on 15 the side of the vat enable the vat-pipe to be held in either elevated or submerged position, as required. By reason of the swivel-connection the pipe may be raised and wiped clean at any time, and allows also for convenient 20 access to the vat, without disconnecting any of the parts, when it is desired to enter the vat after the beer has been withdrawn. By reason of its simple coil the vat-pipe can be wiped with great facility, and because of its 25 arrangement in horizontal plane becomes completely submerged in the liquid, and near the surface thereof, thus utilizing its entire cooling influence at the most effective situation. The coil of the vat-pipe, being wholly at one 30 side of its axis, is raised clear from the liquid, so that no further effect is produced upon the liquid by the continued circulation of the cooling medium.

I am well aware that it has heretofore been

proposed to combine with the stationary supply and return cooling-pipes a vat-conduit 35 swiveled thereto and capable of being submerged in the liquid near the top of the vat.

Having thus described the invention, what I claim as new, and desire to secure by Letters Patent, is—

1. The combination, with the vat, and with the stationary supply and return conduits, of the vat-pipe swiveling about said conduits, said vat-pipe being bent in horizontal coil, and 45 arranged at one side of the axial line of the swivel and near the top of the vat, substantially as described.

2. The combination, with the vat, and with the stationary supply and return conduits for 50 the circulating brine, of the vat-pipe swiveled to said conduits, and arranged in simple horizontal coil near the top of the vat, said vat-pipe being provided with cord and catches, substantially as described, for holding it in 55 raised or lowered position relatively to the vat, substantially as set forth.

3. The combination, with the vat, and with the stationary supply and return pipes for the cooling agent, of the vat-pipe swiveled there- 60 to and sustained in bearings on the vat, substantially as described.

In testimony whereof, witness my hand this 9th day of July, 1884.

DAVID BOYLE.
